Chicago, Ill., a corporation of Illinois

Application May 5, 1945, Serial No. 592,096

7 Claims. (Cl. 179—100.41)

1

This invention relates to transducing devices, and particularly to devices for translating mechanical energy into electrical energy, and vice versa. It has application to transducing devices in which a torsional movement is applied to the transducing element to produce an electrical pulsation, and vice versa. It has especial application to phonograph reproducers and recorders of the crystal type.

In reproducers employing the piezoelectric crystal type of transducing element, commonly called simply a "crystal," the record groove is traversed by a stylus which is supported by a driving member. The undulations of the groove are transmitted by the stylus to the driving member and a coupling member is usually provided for transmitting the vibrations of the driving member to the crystal. While the description hereinafter contained is directed primarily to the use of the device as a reproducer, it may also be used as a recorder and where reference is made in the specification and claims to the driving member and the transmission of energy therefrom to the crystal, it is understood that the direction of energy transfer may be reversed and that it may be transmitted from the crystal to the driving member and from the latter to a recording stylus.

In transducing devices, the more important desiderata are high fidelity of translation, high efficiency, minimum noise and long life. Long record life is also important. As will be apparent from the discussion contained hereinafter, some of these factors are interrelated.

In both reproducers and recorders piezoelectric crystals have been widely employed because of their relatively low cost, small size and light weight. However, they possess certain inherent shortcomings, the most important of which are their great mechanical stiffness, high internal electrical impedance, and fragility.

High fidelity of translation may be obtained only if the force exerted by the stylus tip against the record surface is small. Because the contact area is small, even a small force results in high pressure. High pressure causes deformation of the side wall of a laterally cut groove, and when the pressure is excessive it produces inelastic deformation with consequent distortion, noise and record wear. It has been shown theoretically, and confirmed experimentally, that the vertical force which is required to be exerted on the stylus to keep the stylus tip simultaneously in contact with both sides of the record groove is substantially equal to the horizontal force

2

required to move the stylus tip laterally. This relationship holds for lateral recordings in which the groove side walls subtend an angle of approximately 45 degrees with the vertical and in which the stylus tip radius is sufficiently large that the tip engages the side walls, rather than the bottom, of the groove. This is the usual case. From this it follows that the stylus tip should offer minimum impedance to lateral vibration, where impedance is defined as the quotient of the force by the velocity, both measured in a lateral direction. At low and intermediate audio frequencies the impedance is predominantly that of a stiffness.

15 The problem of driving a torsionally stiff crystal by a driving system which must have low stiffness in order that the stylus may present minimum impedance to lateral vibration was recognized early in the art and was partially met by 20 the introduction of a compliant driving system. This basic principle has been practically universally employed since its early adoption.

Specifically, the problem was dealt with by employing an elastic substance, such as rubber or 25 a synthetic elastomer, as the coupling means between the driving member and the crystal. Such construction is subject to several serious disadvantages, the first of which is that the introduction of the compliance between the driving member and the crystal renders the relative angular displacement of the two dependent on the 30 frequency of vibration and on the masses, compliances and resistances of the driving member and of the crystal and its supports.

35 The second disadvantage is that, although the compliance which is provided serves to reduce the torsional stiffness of the driving member as measured at the stylus tip, the potential energy stored in the compliance member is unavailable 40 to produce strain in the crystal. In the known structures, compliance may be provided in a flexible stylus shank, in the coupling between the driving member and the crystal, and in crystal supports at the end of the crystal remote from 45 the driven end. When the driving member is angularly displaced statically, the displacement is divided among these members and the crystal itself in direct proportion to the relative compliance of the respective members. Under dynamic conditions, a similar effect is present, and the division of the displacement depends upon the frequency. The effect limits the maximum frequency at which the device can be operated satisfactorily.

50 The third disadvantage is that the elastic cou-

pling material deteriorates with age, whereby its elastic properties change and while the operation may be acceptable when the device is new, it becomes progressively and inevitably less satisfactory.

It is an object of the invention to provide a coupling means which transmits the vibrations from the driving member to the crystal in a substantially positive manner whereby the fidelity of translation is high at all frequencies, and substantially all of the energy of the coupling means is available to produce strain in the crystal.

It is another object of the invention to provide a transducing device construction in which the efficiency of translation is high and consequently the ratio of the energy of the signal to that of the circuit noise is high.

It is another object of the invention to provide a coupling means which results in the stylus point having low impedance to lateral vibration.

It is another object of the invention to provide a coupling means which does not undergo any substantial change with age or use.

It is a further object of the invention to provide a coupling means which has a minimum tendency to fracture the crystal.

It is another object of the invention to provide a coupling means in which the angular travel of the driving member is adjustable with respect to that of the crystal.

It is a further object to provide a coupling means which is in the unstressed condition when the device is in the normal or at rest position.

Other objects and advantages will become apparent as the following description progresses, which is to be taken in connection with the accompanying drawings, in which:

Fig. 1 is a plan view of a transducing device of the invention with the top half of the casing removed;

Fig. 2 is a vertical sectional view of the device along broken line 2—2 of Fig. 1;

Fig. 3 is an enlarged isometric view of a portion of the device;

Fig. 4 is a diagrammatic representation of the relative amplitude of the motion undergone by the driving member and the crystal of the device;

Fig. 5 is a fractional plan view of a different modification of the invention;

Fig. 6 is a plan view of a further modification with the top half of the casing removed;

Fig. 7 is a sectional view along broken line 7—7 of Fig. 6;

Fig. 8 is an enlarged isometric view of a portion of the modification shown in Figs. 6 and 7; and

Figs. 9 to 13 inclusive are fragmental views of further modifications of the invention.

The device illustrated in Figs. 1 to 3 is of the torsion type, in which the record has a laterally cut groove and the driving member and the end of the crystal which is coupled thereto undergo angular oscillation about a common axis, while the other end of the crystal is held stationary. The invention is not limited to this particular type of transducing device, but is applicable to other forms as will be pointed out hereinafter.

The device comprises a casing 10 composed of complementary top and bottom casing members 11 and 12, which may be composed of sheet metal or other suitable material and are dished to provide a compartment 13 and have coopera-

tive flanges 14 along the side edges thereof, which flanges are adapted to abut together. At the rearward end, the edges of the casing members are turned inwardly toward each other and are shaped to provide an opening which is closed by a terminal block 15 of electrical insulating material, such as phenol-formaldehyde resin and laminates thereof, etc. The edges of the casing fit into grooves 16 of the block. At the same end, the casing members are held together by means of a bolt 17 which passes through opening 18 in member 12, and at the forward end, the members are held together by a number of bolts (not shown) which pass through openings 19.

At the forward end and also at a point spaced inwardly from said end, the casing members are pressed inwardly to form generally circular bearings 20 and 21, which support a generally cylindrical driving member 22 which is arranged with its axis in substantial alignment with the longitudinal axis of the casing. At locations registering with bearings 20 and 21, driving member 22 has recesses 23 and 24 extending circumferentially, and in these recesses are mounted flexible elastic bushings 25 and 26, which may be composed of natural or synthetic rubber or other suitable flexible elastic material. The recesses 23 and 24 form trunnions for supporting the driving member 22, and the elastic bushings are under compression between the cooperating trunnions and bearings.

A stylus 27 is received in a suitable opening extending generally transversely and diagonally through an intermediate portion of the driving member 22 as shown. The stylus is of the reproducing type but may also be of the recording type, in which case it extends perpendicularly to the driving member axis, instead of diagonally. Stylus 27 extends downwardly through a clearance opening 28 in the bottom casing member 12. The side edges of opening 28 may be adapted to limit the lateral excursions of the stylus beyond a predetermined point. The stylus is clamped in place by means of a clamping screw 29 which is screwed into a threaded opening extending longitudinally into the driving member from the forward end thereof until it intersects the stylus-receiving opening. A collar 30 of rubber or other elastic material extends around the driving member 22 and covers the top end of the stylus-receiving opening, and acts to cushion the top end of the stylus in case the projecting end receives a sudden blow.

In the construction described, the casing 10 is arranged with its longitudinal axis generally parallel to the record groove at the point of contact with the stylus, and the stylus oscillates laterally in response to the undulations of the groove. The oscillations of the stylus are transmitted to the driving member 22 and the latter undergoes angular oscillation about its longitudinal axis. As stated heretofore, the flexible elastic bushings 25 and 26 are under compression between bearings 20 and 21 and trunnions 23 and 24, and there is substantially no relative motion between the bushings and the said parts, but instead the bushings undergo elastic distortion.

Within the compartment 13 and spaced rearwardly of the driving member 22 is the piezoelectric crystal 31, which may be composed of Rochelle salt or the like, and is of the so-called "Bimorph" type, comprising two flat crystal slabs and three electrodes so constructed and arranged as to produce an E. M. F. between the electrodes

upon the application of a torsional moment to the crystal. The structure of such a crystal is well known and is not shown in the drawings. The crystal 31 is in the general form of a thin flat plate of greater length than width and is positioned with its longitudinal mechanical axis of symmetry in substantial alignment with the axis of driving member 22. The rearward end of the crystal is mounted in substantially fixed position between two blocks 32, which may be composed of a rigid or relatively firm material, such as wood, metal, phenol-formaldehyde resin, hard rubber, or a relatively firm rubber or synthetic elastomer, or the like. The surfaces of the crystal may not conform exactly to the surfaces of the blocks, and if rigid blocks are employed, thin pads 33 of an elastic substance, such as rubber, may be interposed between the blocks and the crystal to provide uniform pressure upon the crystal. The thickness of the pads 33 is exaggerated in Fig. 2 for clearness. They are sufficiently thin that the rear end of the crystal undergoes little or no motion. The blocks, pads and crystal are of such dimensions that they are held firmly under compression and may be joined together and to the interior surfaces of the casing 10 by means of an adhesive. The terminal conductors 35 and 36 of the crystal 31 are connected to the bladed terminals 37 and 38 of the device, which pass through and are held in position by terminal block 15.

In accordance with the present invention, improved means are provided for coupling the forward end of the crystal 31 to the rearward end of the driving member 22. This means comprises a bracket or stirrup member 40, preferably composed of a metal strap which extends transversely of the bottom casing half 12 approximately even with the forward end of the crystal 31 and has its end portions 41 and 42 turned upwardly substantially at right angles to the body portion. Stirrup member 40 may be fastened to the casing by soldering or other suitable means. Mounted upon the upper ends of end portions 41 and 42 is a generally V-shaped yoke 44 formed out of a single strip of material having resilient flexibility, such as spring metal. Phosphor-bronze has been found to be satisfactory, but other materials may also be used, such as aluminum, iron or steel, or the like. The end portions 45 and 46 of the yoke are mounted fixedly, as by soldering, upon the upright portions 41 and 42, respectively, of the stirrup 40. From said stirrup member, said end portions 45 and 46 extend rearwardly a short distance and are then turned back upon themselves to form the loops 47 and 48, and then extend forwardly and converge toward each other to form the main arms 49 and 50 which are arranged symmetrically on opposite sides of the axis of oscillation of the driving member 22 and crystal 31. At the loops 47 and 48, the width of the strip is reduced as shown, for a purpose which will be explained hereinafter. At the base of the V, the yoke 44 is widened to form a generally circular, flat section 51 which rests against the rearward end of the driving member 22. The section 51 is connected in positive motion transmitting relationship to the driving member 22 by means of a screw 52 which passes through an opening in the said section 51 and is screwed into a threaded opening or recess in the driving member. A washer 53 is arranged between the head of the screw 52 and the section 51 of the yoke 44.

The portions of the arms 49 and 50 in close proximity to the driving member 22 are necked

inwardly toward each other locally to form sections 55 and 56 which are substantially parallel to each other. An opening is provided in each of the sections 55 and 56 and a threaded bolt 57 passes through the openings and has a nut 58 upon its end. Bolt 57 is adapted for adjusting the distance apart of sections 55 and 56, as will be explained hereinafter.

The main arms 49 and 50 of yoke 44 have slots 10 which are adapted to receive the forward corner portions 60 and 61 of the crystal 31. The said corner portions pass through the said slots and are fixedly joined to the arms 49 and 50 by means of an adhesive or other suitable means, or flexibly attached as by a permanently plasticized cement, or by elastic pads as will be described hereinafter in connection with a different modification of the invention. The yoke is arranged symmetrically with respect to the axis of symmetry of the crystal.

The operation of the device is as follows. As described heretofore, when the device is used as a reproducer, angular oscillation is induced in the driving member 22 by reason of the stylus 23 27 following the groove in the record. The forward ends of the arms 49 and 50 are joined to the section 51 at points on opposite sides of the axis of oscillation and spaced substantially therefrom, whereby they move upwardly and downwardly with the oscillations of the driving member. The rearward ends of the arms are retained against substantial lateral motion by the sections 45 and 46. The narrow loop portions 47 and 48 possess sufficient flexibility to permit ready bending in the vertical direction. The arms 49 and 50, therefore, move vertically or laterally at their forward ends and are substantially stationary at their rearward ends. Such motion will herein be called lateral motion. The lateral motion of the arms is transmitted to the corners 60 and 61 of the crystal. When one of the arms moves upwardly the other moves downwardly and as a result the crystal undergoes a twisting action which produces an E. M. F. in the known manner. The yoke, therefore, constitutes a lever system in which the main arms 49 and 50 constitute the levers and the looped sections 47 and 48 constitute the fulcrums. The arms 49 and 50 are substantially rigid against bending vertically, but possess substantial resilient flexibility in a horizontal direction so that they bend in the presence of a moderate force and also twist a small amount in the presence of a moderate twisting force.

Considering the single lever arm 49, when the driving member 22 induces a downward movement of the forward end of said arm, the rearward end, i. e., the looped section 47, remains stationary and the intermediate portion, i. e., that joined to the corner 60 of the crystal 31 moves downwardly. The arm 49, therefore, is a lever of the second class, i. e., in which the work (the crystal) is located between the fulcrum (section 47) and the force (the driving member). The travel of constricted section 55 determines the travel of the corner 60 of the crystal. The relative travel of these parts is represented diagrammatically in Fig. 4. Solid line 62 and dotted line 63 represent the axis of arm 49 in its upper and lower positions, respectively. Circle 64 represents the path of oscillation of section 55, circle 65 represents the path of oscillation of corner 60 of crystal 31, the line 66 passing through the centers of circles 64 and 65 represents the axis of oscillation, and the point 67 represents the

location of the stationary end of the arm, i. e., loop section 47. While section 55 travels through the relatively large arc 68 of the circle 64, the corner 60 of crystal 33 travels through the relatively small arc 69 of the circle 65. The angular travel of the crystal, therefore, is considerably less than that of the driving member. By angular travel of the crystal and the driving member is meant the angular travel of the ends which drive or are driven by the lever arms. The invention is not limited to the form of driving member shown, and the driving member may possess flexibility and undergo some twisting. The lever arm undergoes some slight twisting due to the restriction against turning at its rearward end, but its resilience is such that such twisting takes place readily. The arm 50 undergoes a similar action but with its direction of motion reversed with respect to that of arm 49, with the result that crystal 31 is given a twisting motion, as explained heretofore.

The angular displacement of the crystal is adjustable. The constricted sections 55 and 56 of lever arms 49 and 50 can be drawn closer together and allowed to move farther apart by their own resilience by turning bolt 57. For a given angular displacement of the driving member 22, when the sections are drawn together, the displacement of said sections is lessened, and the displacement of the corners 68 and 69 of the crystal is also lessened.

In the device described, the motion of the driving member is transmitted substantially positively to the forward end of the crystal and substantially all of the energy imparted to the stylus is available to produce strain in the crystal. The fidelity of translation is, therefore, very high. An additional advantage is that the impedance of the stylus to lateral vibration is small. In the known devices, the impedance is small only when the strain on the crystal is small. In the device of the present invention, the lever system provides a substantially positive mechanical advantage or multiplication of torque applied to the crystal over that applied by the record groove to the stylus, whereby a predetermined safe strain can be applied to the crystal by means of a smaller force at the stylus tip, resulting in reduced stylus wear and record wear. In addition, the mechanical efficiency of the device is high and, as a result, the ratio of the strength of the signal to that of the circuit noise is high. Since the relation between the two displacements, i. e., of the stylus and of the crystal, are fixed substantially positively, they can be established to provide the greatest amplitude of output voltage consistent with safe crystal operation.

As another advantage, the lever system does not have any substantial natural or resonant frequency in the direction of motion of the arms within the range of transmitted frequencies and its transmission characteristics are substantially uniform over said range.

An additional advantage is that the crystal is in the unstressed condition when the device is in the normal or at rest position, that is, when the stylus is not in engagement with the record, and no initial stress is placed upon the crystal in the normal position. A further advantage is that the properties of the transmission system do not change with age.

In the structure described, the arms of the yoke 44 need not be narrowed at the loops 47 and 48 but may be of substantially uniform width and may be made more flexible throughout

whereby bending is distributed along their length.

As explained heretofore, when the device is used as a reproducer, the levers of the system illustrated in Figs. 1 to 3 are of the second class. They may also be of the first class, i. e., in which the fulcrum is located between the force and the work. Such a system is illustrated in Fig. 5, in which the construction and arrangement of most of the parts are similar to those of the corresponding parts of the construction of Figs. 1 to 3 and will not be described in detail. The driving member 70 is mounted for oscillation and is fixedly joined to the base of the yoke 71 by a screw 72. The yoke 71 is mounted fixedly at its end portions 73 and 74 upon a stirrup support 75. The looped portions 78 and 79 serve as fulcrums and relative movement between the lever sections 76 and 77 and the fulcrums 78 and 79 is accomplished by the flexing which takes place at loop sections 78 and 79, which are of reduced width, similar to the sections 47 and 48 of the device of Figs. 1 to 3. Lever arms 76 and 77 are extended rearwardly from the loop sections 78 and 79 by means of extensions 82 and 83 which are joined, as by soldering, to said lever arms 76 and 77. Extensions 82 and 83 are slotted to receive the corners of crystal 84, and thin pads 85 and 86 of an elastic material, such as firm rubber or a synthetic elastomer, are inserted under compression in the slots between the edges of the arms and the top and bottom surfaces of the crystal. The thickness of the pads 85 and 86 is preferably of the order of .01 inch.

In this construction, a lever system is provided substantially similar to that of the construction of Figs. 1 to 3, in which one lever consists of arm 77 and extension 83, and the other of arm 76 and extension 82. The operation of the system is similar to that of the construction of Figs. 1 to 3 with the exception that when the driving member turns in one direction the crystal is twisted in the opposite direction instead of in the same direction. The pads 85 and 86 permit the turning motion which the arms undergo relative to the crystal but transmit the lateral motion of the arms substantially positively to the crystal. This construction possesses all of the advantages described in connection with the device of Figs. 1 to 3.

50 In the modification illustrated in Figs. 6, 7 and 8, the general arrangement is similar to that of the modification shown in Figs. 1 to 3. The device comprises a casing 110 formed of complementary top and bottom members 111 and 112 providing a compartment 113. The rearward end of the casing has an opening which is closed by a terminal block 115. Bearings 120 and 121 are formed in the forward end of the casing, in which are arranged the elastic bushings 125 and 126 which support the trunnions 123 and 124 of the driving member 122. An integral flat blade section 130 extends rearwardly from the driving member 122. The stylus 121 is held in position in driving member 122 by means of the clamping screw 129, and passes through the clearance opening 128 in the bottom casing member 112. The crystal 150, which may be similar to the crystal 31 of the device of Figs. 1 to 3, is located within the compartment 113 and to the rear of the driving member 122.

The yoke 136 serves to couple the crystal to the driving member, and consists of a thin strip of resilient material, such as aluminum, spring bronze, or the like. The arms 137 and 138 thereof are spaced apart at their forward ends and

a vibration damping member 149, composed of an elastic material, such as plasticized cellulose nitrate, may be supported between the arms by an adhesive. The arms extend rearwardly in a diverging direction on opposite sides of the axis of the driving member and at their rearward ends are joined by the transverse yoke section 139. The yoke is in the general shape of a V, with the arms spaced apart at the base of the V and connected together at the top of the V. At the rearward section 139, the yoke is retained in position by blocks 140 and 141 which extend transversely of the casing and rest against the interior surfaces of the casing members 111 and 112, respectively. The arrangement is such that yoke 136 is held firmly in position by the said blocks. The blocks 140 and 141 are composed of a material, such as rubber or a synthetic elastomer, which is elastic and relatively firm. A firmness which produces a reading of from 55 to 70 when tested on the Shore durometer has been found to be satisfactory. As an alternative, one of the blocks may be composed of such a firm material and the other of a soft elastic material, such as plasticized cellulose nitrate. The forward end portions 143 and 144 of the arms of the yoke are bent into planes substantially parallel to the axis of the driving member and spaced uniformly from opposite sides of said axis. They are provided, respectively, with forwardly opening slots 145 and 146. The blade 130 of the driving member 122 is received in the slots 145 and 146, and between the opposing surfaces of the blade and the edges of the slots are arranged thin pads 147 and 148 of a relatively firm elastic material, such as rubber or a synthetic elastomer. Vibration damping members 151 and 152 of an elastic material, such as rubber or plasticized cellulose nitrate, may be inserted between the opposite sides of blade 130 and the interior surfaces of casing 110.

The rearward end portion of the crystal 150 extends through an opening in the rearward section 139 and forward corner portions of the crystal extend through openings in intermediate portions of the arms 137 and 138 of the yoke. An adhesive may be applied so as to join the parts together. The terminals 153 and 154 of the crystal are connected to terminals 155 and 156 of the device, which are mounted in the terminal block 115.

When this modification is employed as a reproducer, the stylus 127 follows the laterally cut record groove and induces angular oscillation in the driving member 122. Such angular oscillation is transmitted by the blade 130 to the forward end portions 143 and 144 of the yoke arms and is transformed into up and down translational motion of said arms. The arms 137 and 138 act as levers in a manner similar to that described in connection with the arms 49 and 50 of the device shown in Figs. 1 to 3. The fulcrums for the levers are the blocks 140 and 141. The said blocks are sufficiently firm that there is little or no vertical movement of the section 139. At the same time, the blocks possess sufficient compliance to accommodate the slight vertical movement of the edges of the rearward portions of the said arms. If one of the blocks is of a softer elastic material, as described hereinbefore, the firm block maintains the lever system in proper alignment while the softer block absorbs some of the vibrational energy at the higher frequencies and thereby provide a smoother response.

At the forward end of the yoke 136, the motion

75

of the driving member results in a torsional stress between the blade 130 and the yoke portions 143 and 144. The blade 130 undergoes rotary or angular motion, whereas the portions 143 and 144 each tend to undergo a substantially linear translational motion within a single plane. The elasticity of the pads 147 and 148 is such that they comply with the stresses and provide a pivotal support for each yoke arm which accommodates any relative turning which the arm and blade tend to undergo. At the same time, the pads are sufficiently thin that there is substantially no lost motion between the driving and the driven members and the energy transmission is substantially positive. An example of a suitable thickness for the pads 147 and 148 is .01 inch, their thickness being exaggerated in Fig. 7 for clearness.

The rearward end of the crystal 150 is restrained substantially positively by the rearward yoke section 139, while vertical motion is transmitted substantially positively to the forward corners of the crystal by the arms 137 and 138. When one of the said forward corner portions is moved upwardly, the opposite corner portion is moved downwardly. In this modification, the lever system applies stress directly to the forward corners and the rearward end of the crystal 50 as to impart a twisting effect to the crystal and thereby generate an E. M. F. The amplitude of travel of the forward corners of the crystal is substantially less than that of the forward portions 143 and 144 of the arms. In this modification and that of Figs. 1 to 3, the levers apply stress to portions of the crystal which are symmetrical with respect to the axis thereof.

The motion of the crystal and the arms is such that the slope of their contacting surfaces, i. e., the edge surfaces of the arms and the top and bottom surfaces of the crystal, is naturally substantially the same. This effect is promoted by the fact that the arms may turn relatively to the blade 130, as described heretofore. As a result the arms exert substantially no bending or shearing stress upon the corner portions of the crystal. Any effect of this character which might be present is accommodated by a twisting of the resilient arms 137 and 138. Any tendency of the arms to shear the crystal may also be avoided by providing rounded edges upon the contacting surfaces of the arms. A twisting effect is imparted to the rearward section 139 of the yoke by reason of the described motion of the arms, and this effect is accommodated by the resilient flexibility of said section 139.

The modification of the yoke which is illustrated in Figs. 9 and 10 is designed to relieve the twisting effect upon the rearward section thereof. The said yoke 160 has a shape generally similar to that of yoke 136 of the device shown in Figs. 6, 7 and 8 and may be arranged in a similar organization. It comprises a rearward section 161 and two forwardly converging arms 162 and 163. The said arms, at points 164 and 165 adjacent to the rear section 161, are twisted throughout an angle of 180°. The twisted sections of the arms introduce vertical flexibility whereby the forward portions move relatively to the rearward portions with a sufficient degree of readiness that the twisting effect upon the rearward section 161 is relieved substantially. With this form of yoke, the effective fulcrums are at the points 164 and 165 and these are preferably arranged to be located approximately one third of the length of the crystal forwardly of the rearward end of the crystal.

11

As explained heretofore, one of the purposes of the coupling mechanism is to cause a reduction of the amplitude of the angular motion of the crystal with respect to that of the driving member. The modification shown fragmentally in Fig. 11 provides a greater reduction factor than do the structures described heretofore. In this modification, a generally channel-shaped clamping member 171 is fitted tightly over the forward end of the crystal 170 and has arms 172 and 173 projecting laterally therefrom. The arms 172 and 173 pass through openings in the arms 174 and 175 of the yoke. The arrangement is otherwise similar to that shown in Figs. 6, 7 and 8. Movement is transmitted by the lever arms 174 and 175 to the arms 172 and 173 of the clamping member 171 and thence to the crystal 170. The amplitude of movement imparted to the crystal for a given amplitude of movement of the lever arms is less than in the device of Figs. 6, 7 and 8.

The modifications described heretofore are adapted for use with a record having a laterally cut groove. The modification shown in Figs. 12 and 13 is adapted for use with a vertically cut groove. The casing 200 is similar to the casing 10 of the device of Figs. 1 to 3, and contains a driving member 201 similar in construction and arrangement to driving member 22 except that the stylus receiving opening thereof extends substantially perpendicularly to the axis instead of diagonally. The stylus 202 is of angular shape, having an end portion 203 which extends into the stylus receiving opening of the driving member 201, an intermediate portion 204 which extends generally perpendicularly to the end portion 203, and a tip portion 205 which extends generally parallel to the end portion 203. The stylus is arranged so that intermediate portion 204 extends generally perpendicular to the axis of the driving member 201 and the tip portion 205 rests in the vertically cut groove 206 of the record 207. The tip portion 205 vibrates vertically, as the device is viewed in Figs. 12 and 13, in response to the undulations of the groove 206, and the end portion 203 vibrates angularly about the axis of the driving member and induces angular vibration of the driving member. The construction and arrangement of the crystal and the means for transmitting motion from the driving member to the crystal may be similar to that of any of the transmitting means described hereinbefore.

While the invention has been illustrated with respect to a twister type of crystal, it is applicable also to a crystal of the bender type. The lever system is also adapted for use with an electrostatic transducing device. For example, it may be applied to the movable electrode 70 of the transducing device shown in Fig. 7 of my Patent No. 2,326,280. It is also adapted for use with a transducing device of the electromagnetic type in which an armature is vibrated or angularly oscillated in an electromagnetic field.

While but a few embodiments of the invention are specifically described and illustrated, it is understood that these are by way of example only, and that various changes may be made in structural features without departing from the spirit of the invention as the same is defined by the appended claims.

What is claimed is:

1. In a transducing device, the combination of a driving member, means for mounting said driving member for angular oscillation about an axis thereof, a transducing element, means for

12

mounting said transducing element at a portion thereof, a pair of levers arranged respectively on opposite sides of and in spaced relation to said driving member axis and extending in the general direction of said axis, means for converting oscillatory motion of said driving member into lateral motion of first portions of said levers respectively, substantially fixed fulcrums for second portions of said levers, said levers having openings therein at third portions thereof, portions of said transducing element remote from said mounted portion thereof extending into said openings, the arrangement being such that lateral motion of said third portions of said levers produces a flexing of said transducing element.

2. In a mechano-electric transducing device, the combination of a driving member, means for mounting said driving member for angular oscillation about an axis, a transducing element, means for mounting said transducing element at a portion thereof, a pair of levers arranged respectively on opposite sides of and in spaced relation to said axis and extending in the general direction of said axis, means for converting angular oscillatory motion of said driving member into lateral motion of first portions of said levers respectively and vice versa, relatively fixed fulcrums for second portions of said levers, third portions of said levers being connected in motion transmitting relationship to a pair of spaced apart portions of said transducing element remote from said mounted portion thereof.

3. The transducing device construction as claimed in claim 2 in which the means for converting angular oscillatory motion of the driving member into lateral motion of the levers includes an arm extending from the driving member transversely of said axis and being in motion transmitting relationship with said levers, and resilient compressible pads between said arm and said levers.

4. In a mechano-electric transducing device, the combination of a driving member, means for mounting said driving member for angular oscillation about an axis, a transducing element of the flexing type, a pair of levers arranged respectively on opposite sides of and in spaced relation to said axis, means for converting angular oscillatory motion of said driving member into oppositely directed lateral motion of first portions of said levers respectively and vice versa, fulcrums for second portions of said levers, third portions of said levers being connected in motion transmitting relationship to a pair of spaced apart portions respectively of said transducing element, and means for holding relatively fixed a portion of said transducing element spaced from said first mentioned portions thereof.

5. In a mechano-electric transducing device, the combination of a driving member, means for mounting said driving member for angular oscillation about an axis, a transducing element of the flexing type, a pair of levers arranged respectively on opposite sides of and in spaced relation to said axis, means for converting angular oscillatory motion of said driving member into oppositely directed lateral motion of first portions of said levers respectively, fulcrums for second portions of said levers, each of said levers being connected in motion transmitting relationship to said transducing element along a substantial portion of the length of said lever, whereby lateral motion of said levers produces a flexing of said transducing element.

6. In a mechano-electric transducing device,

the combination of a driving member, means for mounting said driving member for angular oscillation about an axis therein, a lever, means for converting angular oscillatory motion of said driving member into lateral motion of a first portion of said lever, a fulcrum for a second portion of said lever, a transducing element, means for connecting a third portion of said lever in motion transmitting relationship to a portion of said transducing element, and means for holding relatively fixed a portion of said transducing element spaced from said first mentioned portion thereof.

7. In a mechano-electric transducing device, the combination of a driving member, means for mounting said driving member for angular oscillation about an axis, a yoke having a midsection extending generally perpendicular to said axis and a pair of arms extending from said midsection in the general direction of said axis, means for holding said midsection relatively fixed, means for converting angular oscillatory motion of said

driving member into oppositely directed lateral motion of portions of said arms remote from said midsection and vice versa, said midsection and said arms each having an opening therein, and 5 a transducing element of the flexing type having spaced apart portions thereof extending respectively into said openings in said midsection and said arms, whereby lateral motion of said arms produces a flexing of said transducing element 10 and vice versa.

BENJAMIN B. BAUER.
